AUXILIARY JAWS FOR VISES

Wilhelm Dachauer, Dornbirn, Austria

Application November 23, 1953, Serial No. 393,861

1 Claim. (Cl. 81—39)

2

In the drawings, Fig. 1 shows a side elevation of the auxiliary jaw, a conventional vise jaw being shown in broken lines; and Fig. 2 shows a plan of Fig. 1.

A body 3 of an auxiliary jaw has a recess in its back 5 to receive a jaw 2 of a conventional vise 1. Fastened at a lateral face, inside of the body of the auxiliary jaw, is a threaded stud 7 on which a clamp member 5 is movably guided. Pressure is exerted on the clamp member 5 by threading a nut 6 onto the threaded stud 7. An 10 opposite lateral face of the body 3 of the auxiliary jaw is furnished with a plate 4 which co-operates with the clamp member 5 to mount the auxiliary jaw on the vise jaw 2.

A work-engaging face of the body 3 of the auxiliary 15 jaw is provided with a horizontally extending V-shaped channel 14 and a right-angled channel 15 having one leg parallel to the upper surface of the body 3. The work-engaging face is also provided with vertically extending trapezoidally shaped channels 10, 11, and 13, which form 20 projecting parts 8, 9 and 12, and all of which co-operate with an opposite auxiliary jaw. The opposite auxiliary jaw, which has mainly the same shape as the one shown in the drawing, may be mounted so that its vertical channels confront either the projecting parts 8, 9 and 12, or 25 the channels 10, 11 and 13.

I claim:

An auxiliary jaw for a conventional vise jaw, said auxiliary jaw comprising a body having a plate integrally secured to an end thereof for engaging a corresponding 30 end of such a vise jaw, a threaded stud extending into and secured at the other end of said auxiliary jaw body, a clamp member movably guided on said threaded stud for engaging an opposite side of such a vise jaw, and a nut on said threaded stud for exerting pressure on said 35 clamp member whereby said auxiliary jaw body may be rigidly fastened to a conventional vise jaw.
